UNITED STATES PATENT OFFICE.

WILLIAM BALDWIN, OF CUYLER, NEW YORK.

WASH-BENCH AND WRINGER-HOLDER.

SPECIFICATION forming part of Letters Patent No. 391,933, dated October 30, 1888.

Application filed April 12, 1888. Serial No. 270,433. (Model.)

To all whom it may concern:

Be it known that I, WILLIAM BALDWIN, a citizen of the United States, residing at Cuyler, in the county of Cortland and State of New York, have invented certain new and useful Improvements in Wash-Benches and Wringer-Holders; and I do hereby declare the following to be a full, clear, and exact description of the invention, such as will enable others skilled in the art to which it appertains to make and use the same.

The object of this invention is to provide an improved folding structure to serve as a wash-bench and wringer-holder, the same affording an absolutely firm support and occupying the least possible space when not in use.

To this end my invention consists in the construction and combination of parts hereinafter particularly set forth and claimed.

20 In the accompanying drawings, Figure 1 represents a perspective view of the entire structure embodying my invention in condition for use. Fig. 2 represents a similar view of the same when folded for stowing away. 25 Fig. 3 represents a view of the cap-piece and guide-rods detached from the rest of the structure. Fig. 4 represents in detail perspective one of the shelf-sections.

30 A designates the cap-piece, which is horizontal and provided with a raised rib, *a*, for convenience in grasping it. At the ends of said cap broad ears *a'* extend downward. Pivots *b* pass through these, serving for the attachment to each of said ears of a pair of 35 supporting-legs, *B*, the pivots passing through the upper ends of said legs. Each leg is connected by cross-bars or rungs *B'B'* to the corresponding leg attached to the other ear *a'*. The four legs and their cross-bars thus constitute two sectional frames, folding toward each 40 other and opening into the position shown in Fig. 1.

The upper cross-bars or rungs, *B'*, serve as supports and pivots for two bench-sections, 45 *C*, which are connected together by hinges *c* and provided with overlapping inwardly-extending arms *c'*, the ends *c''* of the arms *c'* of one section fitting within the corresponding

ends *c''* of the arms *c'* of the other section when the shelf is let down into horizontal position. Each bench-section is slatted, leaving openings *c'* for water to pass through. At their meeting inner ends they are recessed to form guide-holes *d*, which fit on guide-rods *D*, that extend rigidly downward from cap-piece *A*.

As the pivot cross-bars *B'* are in line with the sections *C* when these are in horizontal position, said sections effectually lock the legs *B* against inward motion on their pivots until the ends of said sections are raised or their hinges pressed downward. As the weight of the wash-tubs and other articles will be mainly outside of the pivotal lines of said legs, the downward pressure of these articles will only serve to hold the structure as a whole more firmly in the position of Fig. 1. The ends *c''* of the arms *c'* of each section *C* extend under one or more of the slats of the other section to form mutual braces.

When there is no longer any present use for the wash-bench and wringer-holder, it is lifted and the middle part of the sectional shelf bent down so as to slide along the guide-rods, either by a pull or pressure on the hinges or by lifting the outer ends of sections *C*, this motion simultaneously drawing together the pivoted frame-sections made up of the legs *B* and their cross-bars. This operation will be facilitated by inclining the structure toward one side, in order that the weight of the remainder of the frame may aid in folding it. It is restored to the operative position shown in Fig. 1 by merely drawing the frame-sections apart. A slight pull on one leg of each pair will do this.

Having thus described my invention, what I claim as new, and desire to secure by Letters Patent, is—

1. A pair of shelf-sections hinged together and provided with arms extending inwardly from each section under the other, in combination with pivoted frame-sections to which said shelf-sections are pivoted, substantially as and for the purpose set forth.

2. The cap piece *A*, having downwardly-extending ears *a* and guide-rods *D*, rigid

therewith, in combination with legs B, pivoted to said ears, cross-bars B' B², connecting said legs in pairs to form frame-sections, and shelf-sections C, pivoted on the upper 5 cross-bars, B', and connected by hinges opening upwardly, said shelf-sections being recessed to move on said rods, substantially as set forth.

In testimony whereof I affix my signature in presence of two witnesses.

WILLIAM BALDWIN.
